UNITED STATES PATENT OFFICE.

GEORGE H. BOWERS, OF BUFFALO, NEW YORK.

APPARATUS FOR DISPENSING VISCOUS MATERIALS.

Application filed October 3, 1925. Serial No. 60,204.

This invention relates to an apparatus for dispensing or distributing viscous material and although it is primarily designed for applying paste to two or more parts of a core in a mold and also between the opposing surfaces of two parts of the mold itself, such for instance as the drag and cope, it is to be understood that this apparatus is equally useful for a variety of other purposes, such as dispensing or delivering grease for lubricating parts of automobiles or the like, also for applying cement to window frames during the operation of glazing and for other analogous uses.

For the present however this apparatus will be more particularly described in connection with its use as an apparatus for applying paste to cores and parts of molds, as an example of the most important use which has been found for this invention at the present time.

As is well known it is a common practice in foundries to use paste in considerable quantities in connection with molds. In later years due to the production of automotive castings, in which great quantities of cores are employed, the use of paste has been greatly increased. Foundry paste is usually made from a variety of materials, such as wheat flour, dextrine, gluten, etc., the flour being the most common. It has also been the practice in connection with some kinds of work to use hot glue.

In a foundry, paste is used for the purpose of cementing together in one piece two or more parts of a core in order to prevent the hot metal from getting between the parts of the core and thus prevent the formation of fins and also prevent the metal which is poured into the mold cavity from getting into the vents which are provided with outlets through which escape is afforded for the gas and steam generated by the action of the hot metal on the binding material used in the cores. Paste of this character is also used on the surfaces of dry sand molds for connecting the parts thereof and prevent "run outs", that is to say the escape of metal at the joint between the parts of the mold.

It has been the common practice in foundries to mix and keep paste in open containers and to apply it to the joints of cores and parts of molds with a paddle, brush, spoon or small tin can which occasioned the

loss of a great deal of time inasmuch as these methods of operation are very slow and it also was accompanied by a great waste of material owing to the fact that the use of paste in this manner was under poor control. These methods heretofore employed in the application of paste to joints between cores and mold parts also tended to increase the loss of castings because the operator was liable to apply a coat of paste over too large a surface on the cores or mold parts, thereby preventing the easy passage of gases from core to core.

Heretofore in some instances paste has been applied for this purpose by means of squirt cans and grease cans but any gains made by their use are lost on account of the necessity of frequently filling these tools.

As paste for this purpose is better when two or three days old, the open containers in which such paste has been usually stored, particularly in warm weather, attract swarms of flies and give off unpleasant odors. In addition to this such containers are also wasteful inasmuch as thick skins of dry paste form on top of the paste and on the sides of the container during the hours when the paste is set away and not in use and a considerable amount of the paste must therefore be thrown away.

The brush and paddle method above referred to are most commonly used for cementing together the parts of cores and molds and these implements are also the most inefficient owing to the fact that as the paste is applied to the surfaces of the cores or molds the coating of the same is flattened out too much and therefore makes a poor joint between the parts which are to be connected. It has been found very desirable that the paste be laid on the surfaces to be connected in the form of a high ridge or half round ribbon so that when the core sections thus provided with paste are pressed one against the other this paste fills all the interstices and little irregularities in either of the surfaces and makes a perfectly tight joint.

It is the object of this invention to provide an apparatus for dispensing paste or other viscous or paste like material more quickly and easily and with greater uniformity and without waste of material, thereby effecting a substantial economy in the cost of doing this work and also producing a superior

product particularly when used for cementing together the parts of a core or the sections of a mold.

In the accompanying drawings:

5 Figure 1 is a vertical section of the preferred embodiment of my invention showing the same organized for delivering paste and applying the same to the parts of a core or the sections of a mold.

10 Figure 2 is a horizontal section taken on the correspondingly numbered line in Figure 1.

15 Figure 3 is a side elevation, partly in section showing a modified form of my invention as compared with that shown in Figures 1 and 2.

Similar characters of reference indicate like parts throughout the several views.

20 The paste or other viscous material which is to be dispensed, delivered or distributed is stored in a container or chamber which in the preferred organization consists of a cylindrical body 4 which is arranged in an upright position, a lower head 5 which closes the lower end of the body and is connected therewith by means of a screw joint and an upper head 6 which closes the upper end of the cylindrical body 4 and is also connected therewith by means of a screw joint. These 25 several parts of the chamber may be constructed of any suitable material which will enable the same to withstand rough usage and also withstand an internal air pressure equal to the highest which is usually carried 30 in industrial plants.

35 The material which is to be dispensed in this apparatus, such for example as paste intended for coating the cores and mold sections of molds is preferably introduced into 40 the dispensing chamber through an opening 7 in its top, which opening may be covered by a closure of any suitable character for instance a screw plug 8, as shown in Figure 1.

45 This apparatus may be supported in an upright position in any suitable manner for instance by legs 9 preferably three in number which depend from the lower head of the dispensing chamber and are adapted to rest 50 on the floor or other suitable support. In its lower part the dispensing chamber is provided with an outlet for the paste which outlet communicates with the inlet of a flexible hose 10 whereby the paste may be 55 applied to cores or molds located in different parts of the foundry, the application of the paste and the discharge of the same on the cores or mold surfaces being governed by means of a hand controlled valve applied 60 to the outlet end of the delivery hose 10 and provided with a removable discharge nozzle 12. The latter is preferably detachably connected with the outlet 13 of the delivery valve and thus permits of using nozzles of 65 different sizes and thus enable the delivery

of the thickness or size of the stream of paste to be varied in accordance with the character of the work which is to be cemented together. The discharge of the paste from the dispensing chamber through the 70 outlet in the lower part thereof and to the hose 10 and nozzle is effected by air pressure which is introduced into the upper end of the dispensing chamber by means of a pressure pipe 14 extending through the 75 upper head 6. This air pressure may be derived from any suitable source in the plant and as this pressure is usually comparatively high at the source of its generation and only a very slight air pressure is required 80 for forcing the paste out of the dispensing chamber, for example thirty pounds, it is desirable to employ a pressure reducing valve 15 in the air pressure line 14 which pressure regulator may be of any suitable 85 and approved character and of a type now commonly in use for this purpose in air pressure installations. During the operation of this apparatus but very little air pressure is consumed inasmuch as no compressed 90 air is wasted and only a constant pressure is maintained on top of the paste to secure a uniform and effective discharge of the same from the chamber to the outlet nozzle 12.

95 Instead of permitting the paste to flow directly from the dispensing chamber into the delivery hose 10 it is preferable to employ some means for straining or screening this paste and remove therefrom any lumps or solid particles which may be contained 100 therein, such lumps being retained in the dispensing chamber while the paste of uniform consistency is delivered by the hose 10 to the delivery nozzle 12. Although this screen or strainer may be variously constructed, that shown in Figures 1 and 2 has generally the form of an upright cylinder and comprises a lower head 16 which is screwed in a central opening 17 formed in the lower head of the dispensing chamber 110 and provided with an outlet opening 18 which is connected by means of an elbow 19 with the inlet end of the hose 10, a cylindrical upright body 20 secured at its lower end in a pocket formed in the lower head 16 115 and provided with a plurality of perforations 21, and an upper head 22 which closes the upper end of this tubular body. As the air pressure forces the paste downwardly 120 the clear paste flows through the small openings in the body of the tubular screen from all sides thereof to the interior thereof while the lumps or other large particles are retained on the outer side of the tubular screen 20, thereby insuring the delivery only of 125 paste which is of uniform consistency to the surfaces which are to be treated.

130 Means are provided for agitating or stirring the paste within the dispensing chamber so as to break up any lumps which may

be therein and maintain the same as much as possible of uniform consistency, which means are also preferably combined with a wiper whereby any accumulations of lumps or hard material on the exterior of the screen or strainer may be removed therefrom and thus prevent the latter from being clogged and instead maintained in an efficient and serviceable condition. In the preferred construction of this combined stirrer or mixer and wiper the same comprises a horizontal ring 23 which has its periphery arranged close to the bore of the chamber and is adapted to be raised and lowered in the dispensing chamber and to move into and out of the space between the bore of this chamber and the periphery of the tubular screen, this movement being preferably imparted to this agitating or dasher ring 23 by means 20 of an upright shifting rod 24 passing through a stuffing box 25 arranged centrally in the upper head of the dispensing chamber and connected at its lower end with the hub 26 of a bridge which latter is provided with 25 a plurality of legs 27 projecting downwardly from the periphery of the hub 26 at different parts thereof and connected at their lower ends with the top of the dasher ring 23. At its upper end and above the head of the dispensing chamber the shifting rod 24 is provided with a handle 28 whereby the dasher and the parts associated therewith are manipulated. In order to permit of cleaning the outer side of the screen from any lumps 30 or incrustations which may have accumulated thereon a ring-shaped wiper 29 of rubber or other suitable flexible material is mounted on the dasher in position to engage with the peripheral surface of the tubular screen. In the preferred form this wiper ring 29 is arranged on the underside of the dasher ring 23 and is held in place thereon by means of a retaining ring 30 engaging the underside of the wiper and connected with 40 the dasher ring by means of screws 31 which latter upon being tightened operate to clamp the wiper 29 between the rings 23 and 30 and hold these parts securely in position relatively to each other. Upon raising and 45 lowering the dasher the annular wiper 29 slides up and down over the peripheral surface of the screen and brushes therefrom any lumps or similar particles therefrom, thus keeping the openings or meshes of the screen 50 clear and unobstructed and permitting this strainer or screen to be maintained constantly in its most efficient condition.

In the modified construction of this invention shown in Figure 3 the pressure reducing 60 valve 15^a is of slightly different form and arranged at the side of the dispensing tank or chamber instead of at the top thereof and the upper head 6^a has its inlet 7 arranged in a slanting portion 7^a of this head. In the 65 construction shown in Figure 3 the lower

head 5^a of the dispensing chamber is provided with a depressed pocket 32 which receives the elbow 19^a whereby the outlet of the dispensing chamber is connected with the delivery hose 10. The screen in the construction shown in Figure 3 extends over the top of the pocket 32 so as to prevent any lumps or large particles of paste from reaching the delivery hose or tube 10. This screen in the preferred construction bears against 75 an annular shoulder 33 at the upper end of the pocket 32 and is held in place thereon by means of a clamping ring 34 which is connected by means of screws 35 with the lower head. In order to render this screen most effective the same consists of a layer 36 of fine mesh and this in turn is supported on its upper and lower sides by screen layers 37, 38 of coarse mesh thereby securing the screening effect of the fine mesh section and 80 the strength of the coarse mesh section.

In this modified form no special means are provided for agitating the paste within the dispensing chamber or clearing any lumps from the upper surface of the screen but this 90 can be accomplished by any suitable manner.

By the use of this apparatus for dispensing paste or viscous material the waste of paste is practically eliminated and greater efficiency is obtained in the application of 95 paste to the cores and mold parts and this is accomplished with greater ease and facility thereby materially reducing the cost of doing this work.

By the use of the agitator, dasher or mixer 100 a uniform mixture is insured, especially if a refractory substance, such as graphite is mixed with the paste and it also insures a uniform, smooth and free flowing paste which permits of connecting the cores and sections 105 of a mold most efficiently.

When using this dispensing apparatus the application of air pressure to the interior of the dispensing chamber does not cause the paste to be discharged from the nozzle 12 in 110 the form of a spray or atomized paste but instead the paste issues from this nozzle in the form of a small ribbon or viscous stream of paste, the rapidity of the discharge being wholly under the control of the hand operated discharge valve 11. By the use of this apparatus an operator can easily attain a speed much greater than that attained by the hand methods heretofore in use.

The paste does not dry out, the operator 120 only applies what is necessary which results in a substantial saving in the materials of which the paste is made. Furthermore the enclosure of the paste at all times within a container prevents the creation of any 125 odors and therefore avoids attracting any flies.

When this dispensing apparatus is in daily use it does not become clogged or plugged up. The same owing to its small size is 130

portable and can be readily transported from one place to another and a single installation can readily do its work within a radius of forty feet without impairing its efficiency.

5 Furthermore the apparatus permits of laying the paste on the cores and mold sections in the proper way without the presence of any lumps and thereby insures a perfect joint between these parts.

10 I claim as my invention:—

An apparatus for dispensing viscous material comprising a chamber adapted to contain viscous material and provided in its top with a filling opening for introducing the

15 viscous material and an inlet for a pressure

medium and provided in its bottom with a lower opening, a plug secured in said lower opening and having an outlet for the viscous material, a screen having an upright perforated tubular body secured at its lower end 20 to said plug and having its interior communicating with said outlet, a circular stirrer arranged around the tubular body and movable vertically relatively thereto and having its periphery arranged close to the bore of said chamber and a circular wiper secured to said stirrer and engaging the periphery of said tubular body.

In testimony whereof I affix my signature.

GEORGE H. BOWERS.
